UNITED STATES PATENT OFFICE.

WILLIAM H. DRIGGS AND LOUIS LABODIE DRIGGS, OF WASHINGTON, DISTRICT OF COLUMBIA, ASSIGNEES, BY MESNE ASSIGNMENTS, TO THE AMERICAN ORDNANCE COMPANY, OF SAME PLACE.

CARRIAGE FOR FIELD-ARTILLERY.

SPECIFICATION forming part of Letters Patent No. 579,261, dated March 23, 1897.

Application filed May 20, 1895. Serial No. 549,964. (No model.)

To all whom it may concern:

Be it known that we, WILLIAM H. DRIGGS and LOUIS LABODIE DRIGGS, citizens of the United States, residing at Washington, in the 5 District of Columbia, have invented certain new and useful Improvements in Carriages for Field-Artillery; and we do hereby declare the following to be a full, clear, and exact description of the invention, such as will enable 10 others skilled in the art to which it appertains to make and use the same.

This invention relates to improvements in mounts for field-guns; and it consists in certain improvements in the method of mounting the gun upon its carriage, in controlling the recoil thereof independent of the motion of the carriage, in braking the wheels, in strengthening the axles, in throwing the trail-wheel into and out of operation, and thus 20 braking the recoil of the carriage by means of the trail, and in certain other novel arrangements and combinations of parts, as will be hereinafter described and claimed.

Figure 1 represents a sectional view of the 25 field-mount along the broken line $x-x$ of Fig. 2 and looking toward the top of the sheet in the said figure. Fig. 2 represents a plan view of the field-mount, the gun and ammunition-boxes being removed therefrom. Fig. 3 represents a section along the line $y-y$ of Fig. 1 and looking in the direction of the arrows. Fig. 4 represents a section along the line $z-z$ of Fig. 3 and looking in the direction of the arrows. Fig. 5 represents a section along the line $z'-z'$ of Fig. 3 on an enlarged scale and also seen in the direction of the arrows. Fig. 6 represents a similar view to Fig. 4, showing a modified form of the recoil-cylinder for taking up the shock of recoil and for returning the gun to the initial position. Fig. 7 represents a plan view of a modified form of 35 adjusting mechanism for the trail-wheel from that shown in Fig. 1, and Fig. 8 represents a side elevation of the device shown in Fig. 7 as seen from the right of the said figure.

In the drawings the same parts are indicated by the same letters throughout the several views.

A represents the body of the gun, which 50 may be of the Driggs-Schroeder type, as

shown, or of any other desired type. This gun is mounted in the saddle B, which is inferiorly screw-threaded, as at B', to engage in corresponding threads on the body of the gun. This saddle extends downward to form 55 the sliding block B², which slides in the oscillating frame E. The said block B² is perforated to form the double cylinders B⁰, the ends of which are closed by the screw-plugs B³, and the said block is provided with wedge-shaped lugs b, which are dovetailed under the overhanging guides e, attached to the sides E² of the oscillating slide E. Mounted in the cylinders B⁰ are the pistons C, connected to the piston-rod C', whose forward 60 ends are screw-threaded, as at c, and are held in place in the forward end E' of the oscillating slide E by means of the lock-nuts c'. The coil-spring D, interposed between the piston and the closed end of the cylinder, not only 65 assists in checking the recoil of the gun, but will also be of sufficient strength to return the same to the initial position after each discharge.

In the form of recoil-checking apparatus 75 shown in Figs. 1, 2, and 4 the spring D should be made of sufficient strength to absorb a considerable amount of the energy of the recoil, while the springs D' are interposed between the forward end of the cylinder and the oscillating slide for the purpose of checking the gun upon its return to the initial position due to the stored-up energy in the springs D.

In the modification shown in Fig. 6 the cylinder B⁰ is provided with a groove b⁰ to admit the passage of fluid from one side of the piston to the other, and the said cylinder is filled with fluid. The first part of the said groove is made large enough to admit the free passage of the fluid from one side of the piston to the other, whereby the gun recoils freely during the early stages of the recoil, while after the said early stages the groove contracts rapidly, so as to enable the recoil-cylinder to check the recoil of the gun within 90 the desired limits. By this arrangement the gun recoils freely in the line of fire until the projectile has left the muzzle thereof, and the error technically known as "jump" is to a large degree avoided. In this construction 95 100

the fluid in the cylinder serves as a buffer on the counter-recoil, and hence the spring D' (shown in Figs. 1, 2, and 4) may be dispensed with.

5 The oscillating slide E is provided with vertical guides E², which meet together at the front of the said slide in the transverse piece E', to which the piston-rods are attached, as before described. The rear end of this slide 10 terminates in the bifurcated arms E³, across which is pivoted the transverse shaft e³ for the elevating-screw, which will be hereinafter more fully described.

The oscillating slide E is connected, by 15 means of the strap F and tap-bolts f, to the axle G, which is preferably tubular in form, as shown. Thus the oscillating slide is revolvably mounted upon the said axle.

On either side of the strap F are the cheek- 20 pieces K of the trail, which cheek-pieces are stiffened by the bottom plate K' and the top plate K², thus forming a substantially rectangular beam tapering toward the trail-wheel.

25 Mounted on the axle G and fast to the cheek-pieces K are the brackets or supports provided with the plates M for supporting the ammunition-boxes. These plates M are provided with a sleeve M' on the lower side 30 thereof, in which the axle G fits snugly. The said plates M are provided with guide-lugs m' and m, between which the ammunition-box is held, while one side of the plate is bolted fast, as by means of the upturned 35 flange or plate m², to the cheek-pieces K, whereby the said plates are secured rigidly to the said cheek-pieces, thus forming, with the said cheek-pieces, a continuous bracket, which lends rigidity to the entire structure 40 and more especially stiffens the axle, which normally tends to buckle under the excessive strains incident to firing the gun.

The plate M has at the outer side thereof a depending lug M², in which the pawl P is 45 mounted. This pawl P is pressed forward by the spring p, and is provided at its outer end with an eye p' for the ready withdrawal of the said pawl from engagement with the ratchet M³, which is rigidly attached to the inside of 50 the hub of the wheel. This pawl is normally pressed forward by the spring p, but it is provided with a catch p², adapted to be engaged by the lugs q of the latch Q, which latch is made of resilient material and is pressed 55 downward as the pawl P is withdrawn, and then springs upward, engaging the catch p² after the pawl has been withdrawn to the desired distance. In order to disengage the latch, it is provided with a thumb-lug q', which 60 enables the same to be pressed downward, thus allowing the spring p to press the pawl P forward into the holding position.

It will be seen that when the herein-described pawl is in the position shown in Fig. 65 5 the gun may be run forward, while it cannot be drawn to the rear except by dragging the locked wheels over the ground.

The wheels would ordinarily be locked when the piece is "in battery," and the pawl would be withdrawn and held by the catch Q when 70 on the march.

Since the gun would tend to rotate backward about the axle when fired, the elevating-gear must be made of considerable strength, and for this reason the arms E³ in rear of the 75 oscillating slide are made strong and carry pivoted therein a stout bar e³, the center of which is expanded into a nut e⁴, as shown most clearly in Fig. 1.

The elevating-screw R, which is preferably 80 provided with oppositely-disposed threads r and r' and a hand-wheel R', passes through the said nut e⁴, and also through a similar nut s', mounted on the transverse bar s, which is set across the slot k' in the bottom plate K' of 85 the trail. By this construction a simple and strong elevating-gear is provided.

The upper plate K² of the trail is slotted, as at k² in Figs. 2 and 7, to receive the trail-wheel T, which trail-wheel is journaled between the cheek-plates K of the trail.

In the form of device shown in Figs. 1 and 2 the trail-wheel is journaled on an axle t, which is made hollow, as shown, and is adapted to receive the pin v at the end of the lever 95 V, which pin is locked in place when down, as is well known with similar devices. This axle t is journaled at the end of a bell-crank lever U, which is pivoted to the trail at u and is provided with a horn u³, adapted to 100 project downward when the wheel is in the raised position, as shown in Fig. 1, and thus to dig in the earth as the carriage recoils, while the said horn is raised up clear of the ground when the wheel is in the lower position or in the position that it would normally be when on the march.

In order to provide for holding the wheel in the two positions aforesaid, the arm U is provided with two perforations u' and u², whose 110 centers are on the circumference of a circle struck with the pivot u as a center, and the two perforations being adapted to receive the pin v, whereby the said wheel T may be held in the upper or in the lower position, as may 115 be desired.

In the former device (shown in Figs. 7 and 8) the trail-wheel T is mounted on a crank-pin t² on the crank-shaft t', which crank-shaft is operated by the hand-lever t³, which is 120 preferably made resilient and adapted to engage in one or the other of the catches k³ on the side of the trail. The relation of the crank-pin t², the crank-shaft t', and the hand-lever t³ is such that when the hand-lever is turned 125 in one position lengthwise of the trail the trail-wheel will be lifted clear of the ground, as is shown in full lines in Fig. 8, while if the hand-lever be turned in the reverse direction the trail-wheel will be thrown in the 130 lower position, resting on the ground, as indicated by dotted lines in Fig. 8. By this construction a rapid and ready means of throwing the trail-wheel into and out of operation

is provided, and this is especially desirable in the hurry and excitement of bringing the piece into action.

It will be evident that the herein-described mount for field-guns is extremely simple, light, cheap, and durable and that it possesses advantages in construction and facility of operation that will readily suggest themselves to any one skilled in the art.

10 It will be obvious that many modifications of the herein-described invention might be made which could be used without departing from the spirit of the invention.

Having thus described our invention, what 15 we claim, and desire to secure by Letters Patent of the United States, is—

1. In a gun-mount for field-guns, the combination with a gun and a block rigidly attached thereto and carried beneath the gun, 20 with cylindrical chambers in said block, of a rocking slide engaging the sides of the said block and guiding the same, pistons moving in said cylindrical chambers, piston-rods connecting said pistons to said rocking slide, 25 means for controlling the motion of said pistons in said cylinders, an axle and wheels supporting the same, means for pivotally connecting said rocking slide to said axle, a trail, and an elevating-screw connecting said rocking 30 slide with said trail, substantially as described.

2. In a gun-mount for field-guns, the combination with a gun and a block rigidly attached thereto and carried beneath the gun, 35 with cylindrical chambers in said block, of a rocking slide engaging the sides of the said block and guiding the same, pistons moving in said cylindrical chambers, piston-rods connecting said pistons to said rocking slide, 40 means for controlling the motion of said pistons in said cylinders, an axle and wheels supporting the same, means for pivotally connecting said rocking slide to said axle, a trail, and brackets mounted on said axle and rigidly attached to said trail, and supporting the ammunition-boxes, substantially as described.

3. In a gun-mount for field-guns, the combination with a gun and a block rigidly attached thereto and carried beneath the gun, 50 with cylindrical chambers in said block, of a rocking slide engaging the sides of the said block and guiding the same, pistons moving in said cylindrical chambers, piston-rods connecting said pistons to said rocking slide, means for controlling the motion of said pistons in said cylinders, an axle and wheels supporting the same, means for pivotally connecting said rocking slide to said axle, a trail, 55 and brackets mounted on said axle and rigidly attached to said trail, and supporting

the ammunition-boxes, a pawl mounted in each of said brackets, and a ratchet-wheel connected to each of said wheels and normally engaged by said pawl when the gun-carriage is moved backward, substantially as described.

4. In a gun-mount for field-guns, the combination with brackets mounted on the axle, and spring-pawl mounted in said brackets, 65 of ratchet-wheels moving with the wheels of the gun-carriage and normally engaged by said pawls, and means for throwing said pawls into and out of engagement, substantially as described.

5. In a gun-mount for field-guns provided with a trail, the combination with a trail-wheel mounted in said trail, of a crank-shaft journaled in said trail and forming an axle for said wheel, and means for turning said 80 crank-shaft in either direction, for raising or lowering said trail-wheel, substantially as and for the purposes described.

6. In a gun-mount for field-guns provided with a trail, the combination with a trail-wheel mounted in said trail, of a crank-shaft journaled in said trail and forming an axle for said wheel, a lever-arm connected to said crank-shaft and adapted to turn the same in either direction so as to raise or lower said 90 wheel, and catches on said trail for engaging said lever when said wheel is in the raised or lowered position, substantially as and for the purposes described.

7. In a gun-mount for field-guns provided with a trail, the combination with a trail-wheel mounted in said trail, of a crank-shaft journaled in said trail and forming an axle for said wheel, a resilient lever-arm connected to said crank-shaft and adapted to turn the 100 same in either direction so as to raise or lower said wheel, and inclined lugs on said trail adapted to wedge up said resilient lever and to hold the same in the desired direction after it has been sprung between said lugs, substantially as and for the purposes described.

8. In a gun-carriage, the combination with the axle and trail, the latter comprising vertical plates supported on the axle, of a support for the ammunition-boxes at each side 110 of the trail also embracing the axle, each of said supports comprising a sleeve, and guide-lugs, and a horizontal plate all formed in one piece and secured to the trail-plates, substantially as described.

In testimony whereof we affix our signatures in presence of two witnesses.

WILLIAM H. DRIGGS.
LOUIS LABODIE DRIGGS.
